UNITED STATES PATENT OFFICE.

FRED L. REED, OF SYRACUSE, NEW YORK.

JAR-COVER REMOVER.

1,337,158.

Specification of Letters Patent. Patented Apr. 13, 1920.

Application filed November 20, 1919. Serial No. 339,302.

To all whom it may concern:

Be it known that I, FRED L. REED, a citizen of the United States, residing at Syracuse, in the county of Onondaga and State 5 of New York, have invented certain new and useful Improvements in Jar-Cover Removers; and I do hereby declare the following to be a full, clear, and exact description of the same, reference being had to the accompanying drawings, forming part of this 10 specification.

This invention relates to closure removers and has for its object to provide a device for removing the covers of fruit jars and the 15 like.

The usual method of opening preserving jars and the like is to insert a knife or like instrument between the rubber used for sealing the jar and the lower edge of the closure 20 and, by using the knife as a lever, the cover is forced off the jar. When opening a jar in this manner, should the knife slip, serious 25 injury to the hand is likely to result. This liability to injury is entirely eliminated by the present invention.

In the accompanying drawings—

Figure 1 is a plan view of the remover;

Fig. 2 is a perspective view of a portion of a jar with the remover positioned on the 30 closure;

Fig. 3 is a detail sectional view on the line 3—3, of Fig. 1.

As shown in the drawings the opener or remover is preferably made of a single piece 35 of heavy wire bent to form two substantially circular, vertically spaced members A, B, each of which is adapted to surround and engage the greater portion of the periphery of cover C of the jar D. At the end of each 40 of members A and B there is formed a handle E and as the entire device is made of a single piece of material the handles can readily be formed by doubling the wire upon itself, the two reaches of wire forming each 45 handle being spaced apart a suitable distance to afford a better grip on the handles.

Secured in any suitable manner to the cover engaging member A is a short flat piece of metal F which extends downwardly 50 and is attached to the other member B, preferably by soldering, at which point its lower end portion is offset or bent inwardly from member B to form a projection G. As shown, the inner edge H of projection G is 55 sharpened and it is also inclined, thus form-

ing a rather sharp point and facilitating its entry between the jar closure and sealing rubber. Any desired number of projections G may be provided but preferably there are two so positioned on the engaging members 60 A, B that one will enter between the closure and rubber on each side of the jar.

It will be understood that the wire, or other material, used in the manufacture of the device is such as will permit the engaging members to be readily contracted, the resiliency of the material returning the members to their expanded positions. However, to prevent any lateral movement of the two engaging members with respect to each 70 other, the two reaches of wire forming them are wrapped or twisted around each other at a point intermediate their length as indicated at I. The two reaches of wire are also similarly joined at the point I' where the 75 cover engaging members merge into the handles E.

When in use, the remover is placed over and around the jar cover as shown in Fig. 2, the projections G lying substantially in 80 alinement with the bottom edge of the jar cover C. After being thus positioned the handles E are forced together, thus contracting members A and B and causing the projections G to enter between the jar cover and 85 the rubber band used for sealing the jar. This will break the vacuum and generally permit the cover to be lifted off the jar. However, should the cover not be sufficiently loosened, the remover may be rotated a short 90 distance and the projections G will break the seal between the rubber and cover entirely and the cover can then be lifted off.

What is claimed is:

1. A cover remover comprising a contractible cover engaging member adapted to encircle the greater portion of the cover, means for contracting said member around the cover and depending L-shaped members rigidly secured to said engaging member and 95 forming inwardly extending projections movable toward each other when said member is contracted, said projections being positioned below the cover engaging member and adapted to enter between the cover and 100 sealing rubber when said member is contracted.

2. A cover remover comprising upper and lower cover engaging members, means for contracting and expanding said members, a 110

plurality of connections between the cover engaging members, and inwardly extending projections on said connections.

3. A cover remover comprising upper and lower cover engaging members, means for contracting said members, and a plurality of members connecting said cover engaging members and forming a plurality of projections extending inwardly from one of the cover engaging members.

4. A one-piece cover remover comprising upper and lower cover engaging members each adapted to encircle the greater portion of the cover, means for contracting and expanding said members and means carried by said members adapted to enter between the cover and sealing rubber when the members are contracted.

5. A cover remover comprising upper and

lower cover engaging members, means for preventing lateral movement of said members relatively to each other, means for contracting said members, and means carried by one of said members adapted to enter between the cover and sealing rubber when the members are contracted.

6. A cover remover comprising upper and lower cover engaging members each adapted to encircle the greater portion of the cover, handles at the ends of said members, said handles being movable toward and away from each other to contract and expand the cover engaging members, and means carried by one of said members adapted to penetrate between the cover and sealing rubber when said handles are moved toward each other.

FRED L. REED.
